UNITED STATES PATENT OFFICE.

JACOB W. KAISER, OF EAST CLEVELAND, OHIO.

PNEUMATIC RELEASE DEVICE.

1,183,071.

Specification of Letters Patent. Patented May 16, 1916.

Application filed March 16, 1915. Serial No. 14,784.

To all whom it may concern:

Be it known that I, JACOB W. KAISER, a citizen of the United States, residing at East Cleveland, in the county of Cuyahoga and State of Ohio, have invented a certain new and useful Improvement in Pneumatic Release Devices, of which the following is a full, clear, and exact description.

This invention relates to a device for use in connection with gas or air pressure lines, as, for instance, in pumping up of a tire, or in any place where it is desired to release the gas or air when the gas or air has reached a predetermined pressure in the receiver to which the gas or air is supplied.

The object of the invention is to provide such a device that shall be small in its dimensions so that it may readily be carried around from place to place, and further, to provide such a device which is inexpensive to manufacture.

Generally speaking, the invention comprises the elements and combinations thereof set forth in the accompanying claims.

Reference should be had to the accompanying drawings forming a part of this specification, in which—

Figure 1 is a vertical section through the device; Fig. 2 is a vertical section with portions of the device removed; Fig. 3 is a top plan view of a part of the device; Fig. 4 is an elevation with parts in section of a part of the device; Fig. 5 is an elevation of a part of the device; Fig. 6 is a plan view of a part of the device; Fig. 7 is an elevation of a modified form of the device; Fig. 8 is a plan view of a part of the showing in Fig. 7.

In the pumping of automobile tires, it is very desirable that there be some means of ascertaining to just what degree the tires have been inflated. Attempts at this are made by pressure exerted by the hand upon the tire, but this is a rather unsatisfactory method, and it is the purpose of the device herein disclosed to provide a means whereby a tire may be pumped to a definite amount.

I am aware that devices somewhat of this character have been employed in connection with the usual nipple upon a tire, but such devices have not proven practical, largely for the reason that they are constantly becoming damaged and are subjected to all the wear and tear incident to the running of the car.

The device of this invention is very small, in fact it may be conveniently carried in the

pocket of a user, so that it may be with him at all times when he might desire to pump up a tire.

While I have heretofore referred more particularly to the use of this device as useful in the pumping of automobile tires, it will be understood that I do not confine its use to this particular field, for the device will be useful in any connection wherein it is desired to pump air or gas into some container, and to cease pumping gas or air into the container when a desired pressure has been reached.

1 represents the body of the device, the body being provided with a central opening 2. There is an extension 3 from the side of the body 1, which extension is provided with a central opening 4 which communicates with the opening 2 in the body 1. Associated with the opening 4 of the extension 3 is a valve 4^a. This valve may be of any preferred construction, its function being to prevent the escape of air when the pressure in passages 2 and 4 is in excess of the pressure in front of the valve 4^a.

At one end, the body is provided with some means by which it may engage a threaded coupling. For this purpose I prefer to provide a swiveled coupling or union, 85 and to provide for this I form the lower portion of the body 1 with a recess 5 which is adapted to receive an inturned flange 6 of a union 7.

The lower end of the body 1 is recessed, as indicated at 8, and is adapted to receive the cylindrical portion 9 of the union. This cylindrical portion 9 is threaded to receive the threaded end of the coupling. As will be noted, the outer wall of the union 7 is spaced from the wall of the cylindrical portion 9. This space receives the lower end of the body 1. As heretofore explained, the flange 6 is spun or turned inwardly so as to engage with the groove 5, thus securing the union to the end of the body 1, but at the same time permitting relative rotation.

A bridge 8^a, which is a thin wall, extends across the lower end of the passage 2 and into the opening in the gasket associated with the coupling 7. This bridge engages the valve stem of the tire to be pumped and unseats the valve of the tire.

At the opposite end of the body 1 to that which has just been described, the outer surface of the body is threaded, as indicated at 10, and this end of the body is recessed

as indicated at 11. The lower portion of this recess is provided with slanting walls 12, so as to provide a somewhat acute edge surrounding that end of the opening 2 in the body 1 which is adjacent to the recess 11.

Within the recess 11 there extends a pin 13. This pin at its lower end is provided with a cup-shaped portion 14. The cup-shaped portion is adapted to receive some sort of packing material 15. This packing material seats upon the lower part of the recessed portion 11, and forms a closure for the end of the opening 2 in the body 1.

The pin is spaced from the side walls of the recessed portion by means of a washer 16, which is provided with extending points that engage with the side walls, the washer wall opening as much as possible to permit the passage of air under certain conditions, as shown in Fig. 6.

Engaging with the threaded portion 10 is a cap 17, which, upon a portion of its interior surface, is provided with threads that engage with the threads 10.

The cap at its upper end is provided with an opening through which extends the pin 13, and between the washer 16 and the head of the cap 17 there is a spring 18, which yieldingly urges the packing 15 against the bottom of the recessed portion 11. The cap is provided with openings 19 which permit the escape of air when the valve 15 is lifted from its seat.

The body portion 1 is provided with a shoulder 20. Surrounding the body portion 1 beneath the cap is a spring 21, which rests against the shoulder 20. The body portion is provided with a groove 22, which is adapted to receive a projection 23 formed upon a ring 24 which surrounds the body portion beneath the cap 17, the ring 24 being free to slide up and down upon the body portion. The spring 21 engages the under side of the ring 24, yieldingly pressing this ring against the under side of the cap 17. The edge at the open end of the cap is provided with a series of notches 25. These notches are adapted to engage with a ridge 26 formed upon the ring 24. The engagement of the notches 25 with the ridge 26 holds the cap 17 against accidental displacement. The notches 25 are so distributed that they are calibrated with respect to the spring 18, so that these notches represent pressures at which the valve 15 will become unseated against the pressure of the spring 18, and permit the escape of air.

By selecting a proper spring 18, the pressure at which the valve 15 will open may be made practically any desired amount. In devices intended for use upon automobiles the graduations may extend from 40 to 100.

It is desirable to provide some means such that the cap 17 can be turned only through one complete revolution, for obviously if the

cap is set, for instance, to the mark 40, this is correct for only one position of the cap 17. If therefore, the cap 17 were turned a complete revolution and a little more, so as to come back to the graduation 40, obviously the tension of the spring would not be right to release the valve at a pressure of 40 pounds per square inch.

In order to provide for thus limiting the motion of the cap 17, I cut away the threads in the upper part of the cap 17, so as to form a plain walled portion 27. Near the top of the cap 17 there is an opening 28, and upon the upper portion of the body 1 there is an opening adapted to receive a pin 29. In assembling the device, the cap 17 is turned until the opening 28 registers with the opening which receives the pin 29. The pin 29 is then inserted. In this position the pin 29 is substantially against the top of the inside of the cap 17. At least, a very small movement of the cap 17 would bring the pin against the top thereof. This engagement of the pin 29 with the top of cap 17 limits the inward movement of the cap, and in this position the detent in the lower part of cap 17, which is in registry with the holding detent 26 at this time, is the detent which should receive the highest mark, that is to say, in the device shown in this application this detent would be marked 100, for when the device was set in this position the valve 15 would be released when the pressure against it was in excess of 100 pounds to the square inch.

As the cap 17 is turned, the pin 29 would move through the open or recessed space 27 in the cap 17 until the pin 29 engages with a stop which may be the top of the thread upon the inside of the cap, as indicated in Fig. 4 at 28a. This would arrest further movement of the cap, and so lock its outward position. The particular notch 25, which is in engagement with the detent 26 at this time, would be marked the lowest pressure at which the valve 15 would open. In the present instance it would be marked 40, representing the fact that the valve 15 under the conditions, would be opened when the pressure was in excess of 40 pounds per square inch.

In Figs. 7 and 8, I have shown a modified form of the device of my invention. This comprises a body 30 having at one end a threaded extension 31, and at its opposite end a union 32, this union being in all respects the same as that heretofore described and the construction of the union end of the body 30 is the same as shown in Fig. 1. The extension 31 is the equivalent of the extension 3 in Fig. 1, and is constructed in the same manner.

From the body 30 there is an extension 33. The body 30 and the extension 33 are each provided with centrally arranged open-

ings or conduits, which intersect with each other. The end portion of the projection 23 is threaded and recessed in the same manner as described with respect to the body 1, and receives a cap 34 which is constructed in all respects similar to the cap 17. Within the cap 34 is the stem 35, which is spring seated in exactly the same manner as heretofore described. There is, however, 10 a difference in the manner of holding the cap 34 in its adjusted position. The means for holding the cap 34 comprises a spring member 36. This spring member is provided with a rounded portion 27, which is 15 open and surrounds the extension 33. One end of the spring 36 is secured to the body 30, as indicated at 38. The opposite end of the spring 36 is provided with a ridge or detent 38, which is adapted to engage 20 with the notched portion upon the lower portion of the cap 34. It will thus be seen that the spring 36 holds the cap 34 in exactly the same manner as described with respect to the spring 21 and ring 24 in the 25 form of my device heretofore described.

The cap 34 is limited in its outward and inward movement in the same manner as described with respect to my prior device.

Having thus described my invention, what 30 I claim is:—

1. In a device of the character described, the combination with a body member having an opening therein, said body being recessed around one end of said opening, a

valve coöperating with the opening in the 35 recessed portion, a cap member having threaded engagement with the body member, a spring extending between the cap and the valve, one of said members being provided with a groove closed at both ends and 40 the other with a projection engaging in the groove and adapted to limit the inward and outward movement of the cap member, and means for retaining the cap in adjusted position between its limits of movement. 45

2. In a device of the character described, the combination with a body portion having an opening therein, said body being recessed around one end of the opening in the body portion, a valve coöperating with the opening in the recessed portion, a cap having threaded engagement with the body portion, a spring extending between the cap and the valve, said cap having the treads cut away from the upper portion of the interior of the cap, a projection carried by the body portion, said projection being adapted to engage the head of the cap when the cap is turned to the most inward position, and adapted to engage with a stop upon the interior of the cap when the cap is turned to its most outward position. 50

In testimony whereof, I hereunto affix my signature in the presence of two witnesses.

JACOB W. KAISER.
